[57] CLAIM

The ornamental design for a hanger, as shown and described.

DESCRIPTION

FIG. 1 is a perspective view of the front, top and side of my new design.

FIG. 2 is a side view thereof, the other side being a mirror image;

FIG. 3 is a top plan view thereof;

FIG. 4 is a bottom view thereof;

FIG. 5 is a rear view thereof;

FIG. 6 is a front view thereof; and,

FIG. 7 is a side view of a second embodiment of my new design.

The surfaces or portions of the article not shown in the drawing or described in the specification form no part of the claim designed.
